LAMINATED CUSHIONING SOLE
FOR SHOES

Arnold Levin, Brooklyn, N. Y.

Application February 9, 1951, Serial No. 210,228

1 Claim. (Cl. 36—28)

This invention relates to laminated cushioning sole for shoes.

This invention relates broadly to a laminated cushioning sole for shoes, but includes slippers and shoes of not only the type having full uppers and backs, but uppers of all kinds, closed toe, open toe, closed back, and open back.

More especially the invention relates to the construction of an improved cushioning means within the shoe or slipper which will not creep within the shoe or form ridges to cause discomfort to the foot of the wearer, especially at the marginal edges of the inside of the shoe.

Another object of this invention is to provide a cushioned inner sole for a shoe which may be disposed over the full length of the shoe, or may be positioned either at the ball portion or the heel portion of the shoe.

A further object of this invention is to provide in a shoe construction, an insole formed with an upstanding marginal flange or rib within which a portion of a yieldable cushioning member is seated and means is provided whereby distortion of the cushioning member by pressure of a foot thereon will not cause ridges either transversely or longitudinally of the shoe.

A further object of this invention is to provide a cushioned insole construction which can be used with various types and styles of shoes or footwear.

With the above and other objects in view, my invention consists in the arrangement, combination and details of construction disclosed in the drawings and specification, and then more particularly pointed out in the appended claim.

In the drawings:

Figure 1 is a detailed side elevation of a shoe or article of footwear constructed according to an embodiment of this invention.

Figure 2 is a bottom plan view partly broken away of the shoe.

Figure 3 is a fragmentary sectional view taken on the line 3—3 of Figure 1.

Figure 4 is a fragmentary sectional view taken on the line 4—4 of Figure 1.

Figure 5 is a detailed side elevation of a modified form of this invention.

Figure 6 is a fragmentary longitudinal section of the shoe shown in Figure 5.

Figure 7 is a detailed side elevation of another modified form of this invention.

Figure 8 is a fragmentary longitudinal section of the shoe shown in Figure 7.

Referring to the drawings and, first to Figures

1 to 4, inclusive, the numeral 10 designates generally an outsole, and the numeral 11 designates a heel secured to the rear of the outsole. The outsole 10 has secured to the upper side thereof 5 as by adhesive or other suitable fastening means a laminated cushioned midsole structure generally designated as 12. The laminated cushioned midsole structure 12 includes bottom ply 14 which engages the upper side of 10 the outsole 10, and the upper side of the bottom ply 14 has secured thereto as by adhesive or the like an upstanding marginally disposed rib 15. The rib 15 is skived or bevelled as indicated at 16 (see Fig. 4) so as to provide for 15 the substantial merging of the rib structure 15 with the bottom ply 14. A rubber or resilient member 17 is secured by adhesive or other suitable means to the upper side of the bottom ply 14 and projects part way over the upper side 20 of the bevel or skive 16 as shown in Figure 3.

The outer marginal edge of the cushion member 17 which is formed of foam rubber, sponge rubber, or other suitable inherently resilient material terminates inwardly from the upper side 25 of the rib 15 so as to thereby form a space or chamber 18. An upper cushion member 19 is secured as by adhesive or other fastening means to the upper side of the rib or flange member 15 and engages over the upper side of the lower 30 cushion member 17. A fabric member 20 is adhesively secured to the upper side of the upper cushion member 19 projecting about the marginal edges thereof and engaging over the upper side of the rib or flange 15 as indicated at 21 and 35 then extending downwardly as indicated at 22 about the outer edges of the marginal portions of the rib 15. A leather or other flexible sock lining or insole 23 is adhesively secured over the fabric member 20, and an outer midsole 40 covering strip 24 is secured by stitching or other fastening means 25 to the marginal edges of the sock lining 23. The shoe includes a vamp 27 which is interposed between the downturned marginal portions of the sock lining 23 and midsole covering strip 24 so as to be secured thereto by the stitching 25.

The midsole cover 24 is formed with a lower inwardly projecting extension 28 which engages between the outsole 10 and the bottom 45 ply 14 of the cushioned midsole. The extension 28 is adhesively secured between the outsole member 10 and the bottom ply 14. The shoe construction shown in Figures 1 to 4, inclusive, contemplates the provision of a cushioning midsole construction over the entire upper side of

the outsole member 10 and including the shank and heel portion of the shoe.

Referring now to Figures 5 and 6 there is disclosed a modified form of this construction wherein the cushioned midsole construction 12a which is identical with the cushioned midsole construction 12 with the exception that the cushioned structure 12a extends throughout the forepart of the toe portion forward of the shank portion of the shoe.

Referring now to Figures 7 and 8 there is disclosed another modification of this invention wherein the cushioned midsole structure 12b is identical with the cushioned midsole construction 12 with the exception that the insole structure 12b extends from the ball line of the shoe over the heel portion.

The cushioned insole construction hereinbefore described will provide a resilient cushioning means which will cushion the foot in the shoe and will provide for eliminating the ridges which have heretofore been formed in cushioned insoles in prior use. The provision of the chamber 18 between the outer portions of the two cushioned members 17 and 19 provides a means whereby either one or both of the cushioned members 17 and 19 may be distorted outwardly into the chamber 18 without causing any outward appearance of distortion about the marginal portions of the bottom portion construction. The cushioned midsole construction is herein disclosed as being combined with an outsole having a heel secured thereto, but it will be understood that this cushioned midsole construction may be used with various types of shoes which may or may not have heels. When made of the desirable height as can readily be done by suitable planning of dimensions,

the cushion midsole as referred to herein may also be a platform or platform type of shoe or slipper. It will be understood, therefore, that as used herein the term cushion midsole also comprehends a "platform" as such designation is understood in the trade.

What is claimed is:

A laminated cushioned midsole assembly comprising a bottom ply, a marginal upstanding rib 10 secured to the upper side of said bottom ply, said marginal rib being beveled on the inner edge, cushioning means disposed within the area defined by said rib and engaging only the lower part of the upper side of the bevel edge of said rib, a second cushioning ply overlies the first cushioning means and engages the top of the rib, a fabric member secured to the upper side of said second cushioning ply, the marginal edges of said fabric cover member extending downwardly over the outer edge of said rib and secured thereto.

ARNOLD LEVIN.
